GRINDER

Stanley F. Ossing and Oscar J. Feight, Columbus,
Ohio, assignors to The Jeffrey Manufacturing
Company, a corporation of Ohio

Application August 22, 1936, Serial No. 97,436

2 Claims. (Cl. 83—6)

This invention relates to a grinder and particularly to a grinder or shredder for grinding sewage screenings or garbage.

An object of the invention is to provide an improved grinder of the above mentioned class which will be effective to reduce all of the material to a fine or shredded state while keeping the grinding elements of the device free from material at all times, thus providing a very efficient device.

Other objects of the invention will appear hereinafter, the novel features and combinations being set forth in the appended claims.

In the accompanying drawings, Fig. 1 is an end elevational view of the grinder comprising our invention;

Fig. 2 is a side elevational view of the device of Fig. 1;

Fig. 3 is a sectional elevational view taken on the line 3—3 of Fig. 1 looking in the direction of the arrows;

Fig. 4 is a sectional elevational view taken on the line 4—4 of Fig. 2 looking in the direction of the arrows;

Fig. 5 is a transverse sectional elevational view taken on the line 5—5 of Fig. 3 looking in the direction of the arrows, and with rotor omitted;

Fig. 6 is a transverse sectional elevational view taken on the line 6—6 of Fig. 3 looking in the direction of the arrows, and with the rotor omitted;

Fig. 7 is a plan view of the base and grating of the grinder, with the rotor removed, and with parts shown in section;

Fig. 8 is a perspective view of a part of a grating; and

Fig. 9 is a perspective view of a clamping and cutting bar or plate.

The grinder comprising our invention comprises a casing or housing 10 including a base casting 11 and a removably attached top casting section or casting 12. The members 11 and 12 are removably attached together, as by appropriate nuts and bolts 13, to form the enclosing casing for the machine.

The base casting 11 has at each side an arcuate flange 14, which flanges 14, 14 support a screen formed by a pair of arcuate gratings 15, 15, which are of substantially duplicate construction. Each of said gratings 15 comprises a plurality of spaced arcuate grating bars 16 which are rigidly attached to a plurality of transversely extending plates or bars 17, preferably having sharpened noses or edges, as shown in Figs. 3 and 8. The grating bars 16 are each provided with teeth 18 on the inner arcuate portions, which teeth 18 may be

formed by serrating the inner edge thereof. It may be noted that to give strength to the teeth 18 each has a radial face 19 (Fig. 8) which presents a surface substantially at right angles to the direction of the forces exerted in the grinding action.

The arcuate gratings 15, 15 are of similar construction and are removably held in the base casting 11 upon the flanges 14, 14 by toothed plates 21, 22, two of which plates 21 are positioned above one of the arcuate gratings at one side of the base casting 11, and two of which plates 22 are positioned above the other grating 15 at the other side of the base casting 11. That is, the plates 21 and 22 bear against the free or exposed ends of the gratings 15 and keep said gratings in proper positions. Said plates 21 and 22 are held in place in pockets 121 and 122 respectively in the base casting 11 and at their ends and tops abut the top casting 12. Filler plates 123 and 124 are positioned behind the plates 21 and 22 respectively. The plates 21 and 22 are notched to provide teeth 23 and 24 respectively, which are in alignment with the teeth on the grating bars 16 and touch the arc of the circle which is formed by said teeth 18.

To hold the plates 21 and 22 in the pockets 121 and 122 and to provide for their longitudinal adjustment to align the teeth 23 and 24 properly, we provide a cover plate 125 for each pocket 121 and 122, which cover plate is attached to base casting 11 by machine screws 126 and carries a contact plate or washer 127 backed by adjusting washers or gaskets 128 which, with plate 127, are attached to cover plate 125 by a nut and bolt 130, 30 the plates 127 and washers 128 extending into the pockets 121, 122 with said plates 127 in contact with the ends of plates 21 and 22.

The top casting 12 forms a hopper 25, access to which is provided through an opening 26, which 40 hopper 25 directs the material to be reduced, such as sewage screenings or garbage, to the reducing chamber 27 of the grinder.

Carried by the top casting 12 is a preliminary reducing or breaker plate or casting 28 which is 45 provided with a flange 29 at each side thereof, the flanges 29 being attached to the side walls of the top casting 12, as by nuts and bolts 30.

The preliminary reducing or breaker plate 28 is provided with shearing teeth 31, the function of which is explained more in detail hereinafter. Said plate 28 also has a curved lip 32 which cooperates with a V-shaped partition 33 to provide a throat 34 leading to a tramp bin 35. Access to the tramp bin 35 is gained by a removable door 55

36. It may also be mentioned that the partition 33 cooperates to provide the above mentioned hopper 25, and it may be rigidly attached to the top casting 12, by welding, as shown in Fig. 3.

5 To aid in the reducing of the sewage screenings or garbage and also to aid in keeping the interior of the grinder free of adhering putrescible matter, we provide a perforated spray pipe 37 within the hopper 25.

10 Within the reducing chamber 27 is provided a rotor 40 comprising a shaft 41 mounted upon anti-friction bearings 42, 42 carried by appropriate brackets 43, 43 formed integral with the base casting 11 and carrying at one end a fly wheel 44, and at the other end a multiple V-belt type of drive pulley 45.

The shaft 41 extends through openings provided by half-sleeves 47, 47 formed on the base casting 11 and half-cups 48, 48 carried by plates 20 49, 49 which are rigidly attached to the top casting 12, as by welding. It may be mentioned that no material flows out through these openings due to the centrifugal action of the rotor 40 on the material. This centrifugal action also prevents material passing down between said rotor 40 and casing walls without undergoing a reducing action. Spacer plates 50, 50 are interposed between the plates 49, 49 and the side walls of the top casting 12, and welded to each, to provide room for the rotor construction as hereinafter described. Adjacent the forward portion of the grinder, filler plates 150 (Fig. 5) attached by nuts and bolts 151, are provided.

35 Mounted upon the shaft 41 is a plurality of stacked discs or plates 51 and 52, said plates 51 being stacked alternately, and being rigidly attached together by tie bolts 53. Each of the stacked discs or plates 51 and 52 is provided with a plurality of shearing and grinding teeth seen 40 at 54 and 55, respectively, which teeth may be formed by serrating the plate edges axially. The leading edges of teeth 54 and 55 are radial and therefore are parallel with the previously mentioned surfaces 19 of teeth 18 when adjacent 45 thereto, thus cooperating therewith to shear and grind the material and thereby effect an efficient reduction thereof.

It is to be particularly noted that the plates 51 have a larger diameter than the plates 52 and 50 that the teeth 54 travel in a circle, when rotated, such that they pass between the teeth 18 of the grating bars 16, as best illustrated in Fig. 4 of the drawings. The diameter of the circle described by the teeth 55 of plates 52 in rotation 55 is less than that described by the teeth 54 and said teeth 55 rotate in alignment with the grating bars 16, there being only a very small clearance between the tips of the teeth 55 of the discs 52 and the teeth 18 of the grating bars 16, 60 such, for example, as one-eighth of an inch.

65 As clearly seen in Fig. 3 of the drawings, the teeth 31 on the reducing plate or casting 28 are spaced sufficiently away from the axis of rotation of the rotor 40, that there is no overlapping or interleaving between the teeth 54 of the discs 51 and said teeth 31, as said teeth are straight continuous teeth extending completely across casting 28.

In the operation of the device comprising our 70 invention, material to be ground or shredded, such as sewage screenings or garbage, will be fed into the hopper 25 through the opening 26, and will be directed into the reducing chamber 27 where it will be encountered by the rotating 75 rotor 40 which travels in the direction of the

arrow 56. The teeth 54 and 55, and particularly the former, will encounter the material and in cooperation with the teeth 31 of the preliminary reducing plate or casting 28 will effect a preliminary reduction of said material. Complete 5 reduction or shredding of the material will then be effected by the cooperating teeth 54 and 55 and particularly the former, in cooperation with the teeth 23 and 24 of the plates 21 and 22, respectively, and more particularly in cooperation 10 with the teeth 18 of the grating bars 16. The gratings 15 will act both as a screen to retain the material in the reduction chamber 27 until adequately reduced and as grinding elements to co-operate with the rotor 40 to effect such grinding 15 and reducing. Due to the overlapping relation of the teeth 54 and the teeth 18, 23 and 24, there will be a very thorough shredding, grinding or reducing of the material. Furthermore, the teeth 55 in cooperation with the teeth 18, 23 20 and 24 will be very effective to remove from said teeth 18, 23 and 24 any material which tends to accumulate thereon. As a consequence, there will be no appreciable building up of material on the teeth 18, 23 and 24 which would reduce 25 greatly their efficiency, thus presenting the said teeth 18, 23 and 24 substantially clean at all times whereby they will be most effective in performing their reducing operation. The teeth 55 also cooperate with said teeth 18, 23 and 24 to 30 reduce to a very fine state any material caught between them. Any irreducible material, such as scrap metal or tramp iron which is engaged by the rotor 40, will be thrown through the throat 34 into the tramp bin 35 where it may be removed by opening the door 36, mounted upon removable top and bottom supports 136.

In order to insure that no material is thrown upwardly through the hopper 25 by the rotor 40, and also to prevent material flowing into the 40 reducing chamber 27 to the right hand side, as seen in Fig. 3, where it would not be reduced, we provide a block 57 extending laterally completely across said chamber 27 and adjacent the bottom of said hopper, which prevents such 45 action.

It will be evident that the top casting 12 has at its bottom and ends, portions which extend over pockets 121 and 122 and rest upon the plates 21 and 22, thus holding them rigidly against the 50 arcuate gratings 15, 15.

By removing the nuts 13, 13 the top casting 12 may be slid to the left, as viewed in Fig. 2, after a removable plate 58 is removed to free the plates 21 and 22, after which they may be removed by 55 hand, permitting the removal of the gratings 15, 15 by sliding them arcuately around the rotor 40 on the flanges 14, 14 without removing said rotor 40. This provides for ready renewal of the gratings 15, 15 and the plates 21 and 22 without 60 requiring the removal of the rotor 40. To provide access to the bottom of the grinder a removable door 60 may also be provided. Removable side plugs 61 and 62 also provide access thereto from the sides of the casting 11.

65 It is thus seen that a grinder is provided which is particularly adapted for grinding sewage screenings or garbage, preferably with the aid of water, which grinder is very efficient in that the grinding elements are maintained free of any 70 clogging matter at all times.

Obviously those skilled in the art may make various changes in the details and arrangement of parts without departing from the spirit and scope of the invention as defined by the claims 75

hereto appended, and we therefore wish not to be restricted to the precise construction herein disclosed.

Having thus described and shown an embodiment of our invention, what we desire to secure by Letters Patent of the United States is:

1. In a grinder, the combination with a casing, of a rotor mounted for rotation in said casing, said rotor including a shaft and a plurality of 10 stacked plates carrying teeth at their edges, the teeth of alternate plates describing circles of different diameters when rotated, and laterally spaced toothed grating bars in the bottom of said casing forming a grating through which reduced 15 material can pass and positioned so the teeth of some said plates pass between adjacent bar teeth while the teeth of other plates are aligned with other plate teeth, when said rotor is rotated, said grating bars being constructed and arranged to

provide uninterrupted arcuate openings extending over arcs of not less than ten degrees through which reduced sewage screenings pass under the influence of the teeth which travel between adjacent grating bars.

2. In a grinder, the combination with a rotor having a plurality of rows of teeth which travel paths of different diameters, of a casing within which said rotor is mounted, a plate having teeth with a sharp front cutting edge aligned with the 10 rows of rotor teeth which travel the circles of lesser diameter while the rotor teeth of greater diameter pass through the teeth space of said plate, and a grating in the bottom of said casing having teeth cooperating with said rotor teeth 15 and providing an opening through which reduced material passes.

STANLEY F. OSSING.
OSCAR J. FEIGHT.
